UNITED STATES PATENT OFFICE

135,314

DESIGN FOR AN OCTANT

Edward F. Flint, Rochester, N. Y., assignor to
Bausch & Lomb Optical Company, Rochester,
N. Y., a corporation of New York

Application October 17, 1942, Serial No. 108,550

Term of patent 14 years

To all whom it may concern:

Be it known that I, Edward F. Flint, a citizen of the United States and a resident of Rochester, county of Monroe, and State of New York, have invented a new, original, and ornamental Design for an Octant, of which the following is a specification, reference being had to the accompanying drawing, forming a part thereof.

Fig. 1 is a perspective view of an octant embodying my new design.

Fig. 2 is another view in perspective of said octant.

Fig. 3 is a front view of the same on an enlarged scale.

I claim:

The ornamental design for an octant, substantially as shown.

EDWARD F. FLINT.
